(57) CLAIM

The ornamental design for a desktop mount for a mobile electronic device, as shown and described.

DESCRIPTION

FIG. 1 is a top-front perspective view of the design for a desktop mount for a mobile electronic device;

FIG. 2 is a top-rear perspective view thereof;

FIG. 3 is an alternate top-front perspective view thereof, optionally illustrating a mobile electronic device mounted on the desktop mount;

FIG. 4 is a front view thereof;

FIG. 5 is a rear view thereof;

FIG. 6 is a left-side view thereof;

FIG. 7 is a top view thereof; and,

FIG. 8 is a bottom view thereof.

The broken line portions in the drawings are shown to illustrate environment only and form no part of the claimed design.
